LIMITED RANGE WIRELESS TRANSMITTER

Haines L. Knoebel, Philadelphia, Pa., assignor to
Philco Radio and Television Corporation, Phil-
adelphie, Pa., a corporation of Delaware

Application September 22, 1941, Serial No. 411,906

9 Claims. (Cl. 179—100.11)

This invention relates to limited range wireless transmitters such as may be employed in wireless record players, and more particularly the invention relates to wireless record players in which a loop antenna is used to radiate a modulated carrier wave to an associated radio receiver.

In the past it has been common practice to employ record players in which a radio-frequency signal is transmitted from the record player to the radio receiver over the common power line. In such arrangement changes in impedance of the power line may cause changes in the modulation on the carrier, and in many cases certain types of load on the power line will cause hum modulation on the received wave.

It has also been known in the past to use capacitive radiators for transmitting the modulated oscillations of the record player to the receiver, but none of these commonly employed systems has proven entirely satisfactory for reasons which will be explained hereinafter.

It is a principal object of the present invention to provide a limited range wireless transmitter, particularly for use in a wireless record player, capable of supplying a satisfactory signal within a predetermined service area, without creating substantial interference beyond this area.

Another object of the invention is to provide a wireless record player having a loop radiator which may be used at any distance from the radio receiver, but within the predetermined service range thereof, without creating overloading in the carrier frequency stages of the receiver.

Still another object of the invention is to prevent overloading in the input of a loop-equipped radio receiver when picking up a modulated carrier signal from a nearby wireless record player having a tuned loop radiator.

A further object of the invention is to provide simple but effective means for changing the output of a wireless record player over a wide range.

Another object of the invention is to reduce automatically the modulation in the record player when it is desired to use the second harmonic of the modulated wave at the radio receiver.

Other objects of the invention will become apparent from the following description and the accompanying drawing in which the single figure is a wiring diagram of a record player unit embodying my invention.

Referring to the drawing, there is shown a pickup unit 1 which for purposes of this description will be referred to as a crystal phonograph pickup, but which might be any sort of phonograph pickup or might even be a microphone or other translating device, e. g., a short wave converter. This pickup is connected through terminals 2 and 3 of the switch 4 to the control grid 5 of the oscillator-modulator tube 6. Also con-

nected in the circuit of the crystal pickup unit 1 is a compensating network 7 which consists of the resistance 8 and the condenser 9. This network is designed to determine the frequency-characteristic of the crystal pickup 1. In parallel with this network are the serially-connected resistors 10 and 11, the junction point of which is connected to the terminal 12 of the switch 4. The purpose of this arrangement will be explained presently.

The oscillator section of the circuit includes the tapped tank coil 13 together with certain of the electrodes of the multi-grid tube 6. These electrodes comprise the virtual cathode 14, the screen grid 15, the control grid 16, and the anode 17. The circuit resembles a Hartley type oscillator in that the grid and anode electrodes 16 and 17, respectively, are connected to opposite ends of the tank coil 13 (the grid through coupling condenser 18), while the virtual cathode 14 is connected to the intermediate tap on the said tank coil. The virtual cathode 14, which may be constructed in the form of a grid, derives its supply of electrons, of course, from the real cathode 19. The stream of electrons passing from the cathode 19 to the virtual cathode 14 is modulated, however, by the signal on the control grid 5, and thus the output of the oscillator is modulated in accordance with the signal from the phonograph pickup device 1.

In order to provide a predetermined bias between the cathode 19 and the signal input grid 5, a cathode bias resistor 20 may be connected between the cathode and ground, while the bias on the oscillator control grid 16 may be determined by proper choice of a grid leak 21. Plate current for the tube may be derived from a suitable source of direct current B+ by way of the lead 22 and the lower half of the winding 13. Screen current may be derived from the same source by way of the resistor 23, which may be associated with a filter condenser 24. The virtual cathode 14 is preferably connected to a source of constant voltage, such as the source B+, as illustrated.

The circuit is tunable to the desired operating frequency by means of the tuning condenser 25. In accordance with the invention, the tuning condenser is connectable across the whole or a portion of the tank coil 13 by means of switch 26 which is ganged with switch 4. The purpose of this arrangement will be described presently.

Coupled to the tank coil 13 by way of the secondary coil 27, whose midpoint may be grounded, is the loop radiator 28. Preferably the loop 28 is of the low impedance variety disclosed in the copending application of Wm. H. Grimditch, Serial No. 389,987, filed April 23, 1941. In practice this loop may comprise one turn of wire having a generally rectangular configuration, and may conveniently have dimensions, for example, of the order of 8 by 12 inches. The loop may ad-

vantageously be disposed in a vertical plane to better enable reception of the radiated signals by receivers equipped with vertically positioned loop antennas. In one physical embodiment of the invention, the loop was placed in the inside of the rear of the cabinet of the record player, and it consisted of a single turn of flexible multi-stranded large gauge insulated wire.

The use of an inductive link between the loop of the record player and the loop of the receiver offers several important advantages. Equipment of the type described is intended for use only over short distances, e. g., for distances in the nature of less than 100 feet, and it is desired to have rapid attenuation of the signal beyond the usual useful working range of the apparatus.

The field strength of the radiation field set up by the ordinary capacitance antenna varies inversely as the distance, whereas, the magnetic induction field strength set up by a loop, such as the one under consideration, varies inversely as the cube of the distance from the loop and becomes virtually non-existent shortly beyond the useful range of the device. Thus, it is apparent that a relatively strong field may be used in the desired working range without creating an extensive interfering field.

In the operation of the device in accordance with the invention, if the record player is some distance from the radio receiver, e. g., more than 4 or 5 feet, the gang switches 4 and 26 are set as shown. Under these conditions the entire voltage developed across the pickup 1 is applied to the grid 5. Likewise, the tank tuning condenser 25 is connected through the switch 26 across the lower half of the tank coil 13. This condenser is preferably adjusted to tune the plate circuit to a suitable frequency in or near the broadcast band, say from 540 to 570 kc. The voltage applied on the control grid 5 will then modulate the oscillations which are occurring in the oscillatory circuit of the tube and will result in a modulated voltage wave appearing in the coil 13. This modulated oscillatory wave will be transferred to the coil 27 and radiated from the loop antenna 28, and may be picked up within the service range of the device by a radio receiver tuned to the oscillator frequency.

If it is desired to operate the record player a very short distance, e. g., less than 4 or 5 feet, from the radio receiver, it may be found that the strength of the signal radiated will be such as to cause an excessively high voltage, for example, in the nature of one volt or even more, to appear on the input of the first tube of the receiver. This may result in an abnormally strong AVC action in the receiver with resulting distortion, or may even cause the receiver to go into R. F. oscillation with blocking of the incoming signal.

It is, therefore, desirable to reduce the output of the record player under such conditions by a wide margin, for example, by a 100-1 ratio. However, changing the output of an oscillator circuit over so wide a range is not easily accomplished, since the stability and other desired characteristics of the oscillator depend on maintaining a predetermined optimum output level. According to the present invention, the output level of the oscillator may be maintained substantially constant, while the frequency is reduced by one half, so that the wave picked up by the receiver under these conditions is the second harmonic of the oscillator wave, rather than the fundamental. Since the power contained in a harmonic is normally small, it may easily be arranged to have 75

the amplitude of this wave bear the desired ratio to that of the fundamental. As will be explained in detail hereinafter, the operating frequency of the oscillator may be altered by changing the resonant frequency of the tank circuit.

It has been found, however, that when the percentage of modulation is adjusted to afford optimum reception of the fundamental wave, the second harmonic wave will be seriously over-modulated, and considerable distortion will result unless means are provided for substantially reducing the degree of modulation under these conditions. In further accordance with the present invention, means are provided for reducing the magnitude of the modulating potential during second-harmonic operation of the wireless record player. Experience has shown that the modulating signal is best reduced in magnitude by 50% or more during second harmonic operation, and in one satisfactory embodiment of the device it was found desirable to reduce the modulating signal to 35% of that employed during normal or fundamental operation. This reduction is accomplished in the record player constructed in accordance with the invention by adjusting the gang switches 4 and 26 to their second position. The crystal pickup is now connected to the grid 5 of the tube through the voltage divider circuit consisting of the resistors 10 and 11, and the voltage applied to the grid 5 is reduced in the ratio of

$$\frac{r_{10}}{r_{10} + r_{11}}$$

35 The tuning condenser 25 is now connected across the whole tank coil 13 rather than across only a portion of it, as in normal operation. If the total inductance of the tank coil 13 is properly related to the inductance of the anode portion 40 thereof, it will be possible approximately to halve the resonant frequency of the tuned circuit when the condenser is shunted across the entire coil as compared to when it is shunted across only a portion thereof. The proper turns ratio between the two portions of the coil is best arrived at by trial, but in general, where a single tuning condenser is employed, as shown in the drawing, the inductance in the resonant circuit at the lower frequency should be approximately 45 four times the inductance in the resonant circuit at the higher frequency. The record player will now operate in the same manner as previously described excepting that the voltage applied to the grid 5 will be materially lower and the frequency of the oscillator will be approximately one-half of its normal frequency, and the radio receiver, instead of receiving the fundamental of the oscillator frequency, will receive the second harmonic. This second harmonic may be weaker 50 than the fundamental in the order of about 1-100 and the voltage imposed on the receiver will, therefore, be well within the limits required for satisfactory reception.

In order to permit the changing from the 65 "local" position to the "distance" position of the switch 4-26, or vice versa without retuning the receiver to a new frequency, it is essential that the frequency of the oscillator on "local" be exactly one-half the frequency of the oscillator on "distance," so that the second harmonic in the first case will be substantially the same frequency as the fundamental in the second case. While the above-described embodiment of the invention uses one-half frequency and the second harmonic, it is contemplated that one-third

frequency and the third harmonic, or any higher harmonic, might be used. The third harmonic may be found especially useful in circuits employing pentodes, as pentodes are rich in third harmonics.

The oscillator-modulator circuit may employ one of the converter tubes such as are widely used in superheterodyne receivers. A 6A7 tube, for example, is suitable for the purposes of the invention. However, any one of the many well-known separate or combined oscillators and modulators may be employed.

While the invention has been illustrated and described in its specific application to a record player for which it is particularly intended, it is, obviously, capable of use in any instance where it is desired to transmit a signal within a short distance range regardless of the particular source of such signal.

I claim:

1. A wireless record player or the like, comprising a source of current of modulating frequency, an oscillator, a modulator, and a radiator, means for changing the frequency of the oscillator so that the frequency which is to be picked up is either the fundamental or the second harmonic of the oscillator frequency, and means for simultaneously changing the modulation so that the percentage modulation is reduced when the frequency which is to be picked up is the second harmonic of the oscillator frequency.

2. A wireless record player as defined in claim 1, in which the radiator is an inductive loop.

3. A wireless record player or the like, comprising an oscillator, a source of modulating current, means for modulating the oscillator with said current for transmitting a modulated wave to a radio receiver at a predetermined frequency, said predetermined frequency being optionally either the oscillator frequency or twice the oscillator frequency, and switch means to reduce the degree of modulation when the predetermined frequency is twice the oscillator frequency.

4. In a wireless transmitter for transmitting a desired signal to a radio receiver within a short distance range, means for generating a carrier wave, means for modulating said carrier wave with said desired signal, means operable at will to change the frequency of said carrier wave in the ratio of n to 1, where n is an integer greater than 1, and means for simultaneously varying the degree of modulation of the carrier wave whenever its frequency is changed by said last-named means.

5. A wireless record player, comprising means for generating a carrier wave, a signal pickup device, means for modulating said carrier wave with the signal from said device, means operable at will to change the frequency of said carrier wave in the ratio of n to 1, where n is an integer greater than 1, and means for simultaneously varying the degree of modulation of the carrier wave whenever its frequency is changed by said last-named means.

6. In a wireless transmitter for transmitting a desired signal to a radio receiver within a short distance range, means for generating a carrier wave, means for modulating said carrier wave with the desired signal, means for changing the frequency of the generated wave so that the frequency which is to be picked up is either the

fundamental or a harmonic of the generated wave frequency, and means for simultaneously changing the degree of modulation of the generated carrier wave whenever its frequency is changed by said last-named means.

7. A wireless transmitter for transmitting a desired signal to a radio receiver from different positions within a short distance range of the receiver, comprising means for generating a carrier wave of predetermined frequency suitable for operation of the receiver over the greater distances in said range with the receiver tuned to said frequency, manually operable means for changing the frequency of the generated carrier wave to a predetermined fraction of said first-named frequency to operate the receiver over very short distances without changing the tuning of the receiver, thus causing the receiver to receive a harmonic of the fractional frequency, whereby the transmitter is operated at substantially constant output but the signal received at the receiver is substantially varied in strength, and means for modulating the carrier wave with the desired signal during either of the aforesaid transmitting operations.

8. A wireless transmitter for transmitting a desired signal to a loop-equipped radio receiver from different positions within a short distance range of the receiver, comprising means for generating a carrier wave of predetermined frequency suitable for operation of the receiver over the greater distances in said range with the receiver tuned to said frequency, manually operable means for changing the frequency of the generated carrier wave to a predetermined fraction of said first-named frequency to operate the receiver over very short distances without changing the tuning of the receiver, thus causing the receiver to receive a harmonic of the fractional frequency, whereby the transmitter is operated at substantially constant output but the signal received at the receiver is substantially varied in strength, means for modulating the carrier wave with the desired signal during either of the aforesaid transmitting operations.

9. A wireless transmitter for transmitting a desired signal to a radio receiver from different positions within a short distance range of the receiver, comprising means for generating a carrier wave of predetermined frequency suitable for operation of the receiver over the greater distances in said range with the receiver tuned to said frequency, manually operable means for changing the frequency of the generated carrier wave to a predetermined fraction of said first-named frequency to operate the receiver over very short distances without changing the tuning of the receiver, thus causing the receiver to receive a harmonic of the fractional frequency, whereby the transmitter is operated at substantially constant output but the signal received at the receiver is substantially varied in strength, means for modulating the carrier wave with the desired signal during either of the aforesaid transmitting operations, and a loop radiator for effecting transmission to the receiver loop through magnetic induction.

10. A wireless transmitter for transmitting a desired signal to a radio receiver from different positions within a short distance range of the receiver, comprising means for generating a carrier wave of predetermined frequency suitable for operation of the receiver over the greater distances in said range with the receiver tuned to said frequency, manually operable means for changing the frequency of the generated carrier wave to a predetermined fraction of said first-named frequency to operate the receiver over very short distances without changing the tuning of the receiver, thus causing the receiver to receive a harmonic of the fractional frequency, whereby the transmitter is operated at substantially constant output but the signal received at the receiver is substantially varied in strength, means for modulating the carrier wave with the desired signal during either of the aforesaid transmitting operations, and means for varying the degree of modulation of the carrier wave simultaneously with the change in frequency thereof.

HAINES L. KNOEBEL.
